UNITED STATES PATENT OFFICE.

DAVID M. DEARING, OF DENVER, COLORADO, ASSIGNOR TO GUILFORD S. WOOD, OF DENVER, COLORADO, AND HENRY P. DEARING, OF SANDSTONE, MICHIGAN.

ROTARY ENGINE.

SPECIFICATION forming part of Letters Patent No. 693,348, dated February 11, 1902.

Application filed November 15, 1897. Renewed December 13, 1901. Serial No. 86,812. (No model.)

To all whom it may concern:

Be it known that I, DAVID M. DEARING, a citizen of the United States, residing at Denver, in the county of Arapahoe and State of Colorado, have invented certain new and useful Improvements in Rotary Engines; and I do hereby declare the following to be a full, clear, and exact description of the invention, such as will enable others skilled in the art to which it appertains to make and use the same.

This invention relates to steam-engines, and more especially to that class thereof known as "rotary;" and the objects of the same are several. In the first place it is well known to those familiar with engines of this type that the excessive wear between the parts and the resultant escape of steam or the resultant friction is so great as to soon destroy the efficiency of the machine, to which fact may be due the further fact that rotary engines have not as yet gone into extensive commercial use. My invention contemplates the use of a rim and a core and in the latter a radially-movable cylinder-head; and the first and primary object thereof is to produce means for overcoming the friction between the rim and head, whereby the above objection will be avoided. In the second place it is well known that such types of engines as apply the full force of the live steam to drive the piston produce greater power but consume more steam than those types wherein the expansive force of the steam is used to all or some of its extent to do this work, and the second object of my invention is to produce a rotary engine which is so constructed as to be capable of using the live steam under its full force at desired times and in connection with the expansive power of the steam at all times, thus gaining the advantages of both means of using the working power of steam. In the third place it is well known that rotary engines possess other disadvantages—such as the objectionable "dead-center," the inability to be started and stopped either under expansion or under full head of steam, and the necessity of so shaping their surrounding rims as will produce the desired results—and the third object of

my invention is to overcome these and other objections, as well as to produce improvements in the details of construction.

The several objects above are accomplished by the construction set forth below and pointed out in the claims, all as also illustrated in the accompanying drawings, wherein—

Figure 1 is a cross-section of this improved rotary engine, taken on line $y-y$ of Fig. 2. Fig. 2 is a longitudinal section thereof, taken on the line $x-x$ of Fig. 1. Figs. 3 and 4 are inner face views of the disk of Fig. 14 and the ring of Fig. 16, shown as in position upon the end plates of the casing. Figs. 5 and 6 are sectional views through the outer edges of these parts to illustrate their cam-grooves. Fig. 7 is a section through the core, its flanges, and said rings, as well as a section through the cylinder-head at a proper point to show the operation of the cut-off plate. Fig. 8 is an elevation of a portion of the spindle forming part of the steam-inlet. Fig. 9 is an elevation illustrating the application of my engine to drive a propeller. Fig. 10 is a similar view illustrating the use of two of my engines set "quartering" on the shaft of a locomotive or the like for driving the same. Figs. 11 and 12 are sections taken on the lines $v-v$ and $w-w$ of Fig. 8, respectively, and including also some of the parts surrounding the spindle. Fig. 13 is a cross-section of an engine whose rim is built with an active face struck on arcs of two circles. Fig. 14 is an elevation of the said disk, Fig. 15 of one of the flanges for the core, and Fig. 16 of said ring. Fig. 17 is a section similar to Fig. 13, showing an engine whose rim has an active face struck on the arcs of three circles. Fig. 18 is a detail showing the two rings, partly in section, and illustrating the valve-throwing device. Fig. 19 is a detail illustrating the use of rods and pulleys in a modified form for causing proper movements of the cylinder-heads.

Referring to the drawings by reference-numbers, 5 designates the bed and supports for the tubular shaft 6^a , which is held against rotation by any suitable means. Through this shaft is passed a double valve-spindle 15, preferably made slightly conical, as shown in

Fig. 2, and operated by a handle 19, secured upon its smaller end and adapted by contact with the packing-nut 18 on the end of the shaft 6^d to be drawn or moved longitudinally 5 to a slight degree for the purpose of taking up wear and preventing the escape of the fluid agent. However, any suitable means could be employed for this purpose. Said spindle 15 is cored at one end with an inlet- 10 passage 15^a and at the other end with an exhaust-passage 30, there being any suitable form of closure or wall between the inner ends of these passages.

17 is an inlet-pipe from the boiler or other 15 source of supply of the fluid agent under pressure, and 17^a is an opening in the spindle 15 of a size to communicate with the inlet-pipe at all times when the engine is running.

8 designates a rim, preferably cylindrical 20 on its exterior. To the open ends of this cylindrical rim are detachably or rigidly attached, as by bolts or screws 6^e, the end plates 7, having enlargements or hubs at the points where they are journaled on the shaft 6^d. One 25 or both of these hubs can serve as pulleys from which power generated by this engine can be transferred to the machinery which it is desired to drive, or the driving-belt could be placed directly around the rim 8, if so desired. 30 I preferably employ a collar 16, which is adjustably mounted on the shaft 6^d and serves to hold the rotary rim and its end plates and hubs in proper position between the supports 5. The inner face of the rim 8 has grooves 35 8^b at its ends, which are truly concentric to its shaft for a purpose to appear below, but between them the active face 8^a, forming one of the walls of the steam-space 13, is struck on a plurality of curved lines. The latter 40 are shown in Figs. 13 and 17 as forming arcs of true circles, although they may be struck on lines deviating slightly therefrom, as in Fig. 1, without necessarily departing from the spirit of my invention. At all points where 45 these curved lines intersect each other are located the piston-heads 9^a, here shown as any suitable packing, pressed inward by screws 57.

6 designates a core fast on the shaft 6^d, truly cylindrical in form and of the same length 50 axially as the active face above mentioned, while 6^f are truly cylindrical flanges secured to the opposite ends of this core and provided with suitable packing in their outer edges which travel in the grooves 8^b near the ends 55 of the rim. I might here state that although in the present instance I have everywhere shown the core and its parts as stationary and the rim and its parts as rotary it will be understood that the reverse might be the 60 case—in other words, the rim might be fixed and the core revolve within it (by making slight changes in the construction) without necessarily departing from the spirit of my invention. At suitable points in the periphery of the core are formed chambers 6^a, preferably radial thereto, and in each chamber is

mounted for longitudinal movement a cylinder-head 10, having suitable packing 75 along its outer edge adapted to coact with the active face of the rim, and hence of the same 70 length as the width of such face. The ends of these heads will also carry suitable packing adapted to coact with the inner faces of the flanges 6^f to prevent leakage.

In the ends of each cylinder-head are mounted pins 10^a, which project through slots 6^e in the flanges 6^f and travel in cam-grooves 12, that are formed in the inner faces of disks 7^a, which are attached by screws 7^c to the end plates and revolve therewith. (See Figs. 4 80 and 14.) These cam-grooves are struck on lines absolutely parallel with said active face of the rim, being an exact reproduction of form thereof, and hence as the rim and disks revolve the cam-grooves by their engagement 85 with the pins cause the longitudinal movements of the cylinder-heads at precisely the proper moments and to exactly the proper extent to prevent undue friction between the heads and active face along their coacting 90 lines, and yet by means of the packing 75 to prevent the escape of the fluid agent.

As a modification of the above and for use in large machines pulleys 10^b could be substituted for the pins or journaled thereon and 95 travel in slightly-larger grooves, or rods 10^c could extend from the cylinder-heads inward and carry the pins or pulleys at their inner ends nearer the axis, and hence reduce the length of travel and consequent friction. (See 100 Fig. 19 and the dotted cam-grooves in Fig. 1.) This idea of having the longitudinal movements of the heads controlled not by their contact with the active face or by springs, but by means of the cam-grooves remote from the 105 coacting points or lines between the heads and active face, forms the primary or main point of the present invention, and I consider it especially valuable for reasons elsewhere stated.

At suitable points in the cam-grooves 12 and possibly where they are nearest the axis, as at 12^a, may be formed air-ports 12^{aa}, opening to the exterior air or into the exhaust, whereby I prevent the formation of air-cushions in the chambers 6^a behind the heads as the latter recede. The spindle 15 is provided near its center with several ports opening from its cored passage 15^a radially outward, as shown in Fig. 8, there being four 110 inlet-ports 15^b at one side of the central wall, Fig. 11, and two outlet-ports 15^d at the other side thereof, Fig. 12. The core 6 is provided with radial inlet-ducts 6^b, two for each cylinder-head, leading from points in the periphery of the core adjacent opposite faces of the head inward through suitable individual openings in the shaft 6^d to its bore, wherein is mounted the spindle 15. These inlets preferably stand in a plane near one end of the core, and four similar outlet-ducts 6^c are arranged in another plane within the core and 115 120 125

shaft near the opposite end. The inlet-ducts connect with the inlet-ports and the outlet-ducts with the outlet-ports, as will be clear. The cylinder-heads are preferably never set exactly diametrically opposite each other, a slightly or approximately quartering position preventing dead-centers, as usual, and the dotted positions in the several views illustrate other positions which these heads could occupy.

7^b designates rings surrounding the disks above described and preferably having slots 11^c, through which screws 11^d pass loosely into or through the casing-plates 7, for a purpose to appear later. These rings rotate with the rim outside the flanges 6^f, and their inner faces are provided with two concentric cam-grooves 11 and 11^a when the cylinder-heads are not directly opposite each other; but only 20 one such groove will be necessary when these heads are diametrically opposite. 20 are cut-off plates sliding longitudinally within the core parallel with its axis and having rounded ends projecting into these cam-grooves, as seen in Fig. 7. Each cut-off plate has a pair of slots 20^b of sufficient length to span the outlet-ducts 6^c, so as to leave them always open, and between these slots an opening of sufficient size to permit the passage of the head 10 and of proper length to permit the above movements of the plate thereover. On opposite sides of this opening each plate is also provided with holes 20^a, of which each is twice the length—lengthwise of the plate—of the respective inlet-ducts 6^b, with which these holes are adapted to register, and such holes are so arranged that the left or inner end of one is in alinement with the right or outer end of the other. The object of this construction is set forth below. The cam-grooves and their shallower and deeper parts are so located that their action on the cut-off plates 20 shall be properly timed to effect the cut off of live steam in the inlet-ducts 6^b at proper moments.

With the construction of this improved engine as thus far described the operation will be as follows: The parts standing as seen in Figs. 1 and 2, steam is admitted at 17, passes along the core-passage 15^a, out the port 15^b, along the duct 6^b, and into the steam-space 13 at the left of Fig. 1; between the cylinder-head 10 and the piston-head 9^a. The latter being on the rotary rim, the full force or initial pressure of the live steam or other agent is applied to rotate the rim to the left, as here shown. As soon as this rim has turned fifteen degrees (more or less) and while the first steam-chamber is still using steam the other piston-head 9^a passes the other cylinder-head 10 and a new steam-chamber is formed, (near the top in Fig. 1,) so that the full force is applied at that point to continue the application of power. Approximately the same action takes place in Figs. 13 and 17. In all cases it will be understood that the cam-

grooves and pins or pulleys cause the inward and outward movements of the cylinder-heads to correspond exactly with the shape of that portion of the active face of the rim which is opposite. The exhaust-duct 6^c is always open at the forward end of the steam-space 13 just in rear of the next cylinder-head, just behind the full-lined inlets shown in the drawings, and hence not capable of illustration thereon. When the rim has turned and the piston-head 9^a has moved for a distance preferably between a quarter and a half of the length of the stroke, the high point 35 of the cam-groove 11 in ring 7^b throws the cut-off plate 20 to the opposite position, thus closing the inlet-duct 6^b, after which the steam expands in the chamber 13 during the balance of the stroke. The same action takes place with the other piston-head and its plate 20, though operated by the other cam-groove 11^a.

In order to reverse the direction of rotation of this engine it is simply necessary to turn the handle 19 and its spindle 15 until the ports in the latter move from the position shown at the right of Fig. 11 along the direction indicated by the arrow therein to the position shown at the left of this view. The inflowing steam or other agent then passes to the other set of ducts 6^b and to the opposite sides of the heads 10 from that shown in Fig. 1, and obviously the direction of rotation will be reversed. By this process the ducts formerly open have been closed, while those formerly closed have been opened, and this applies to both the steam inlet and exhaust ports. This reversing action is the same in the several forms of my machine illustrated herewith.

When it is desired to have the cut-off take place at different points in the length of the stroke from those above described, the screws 11^d are loosened, the rings 7^b turned relatively to the disks 7^a, and the screws reset at the desired and proper points in the slots 11^c.

This engine can be stopped at any time by means of an ordinary throttle in the steam or other feed pipe 17 or by turning the spindle 15 to such an extent that none of its inlet-ports 15^b will register with the inlet-ducts 6^b. If, however, the engine is stopped after the cut off of live steam has taken place—i. e., on expansion—it will be necessary to in some manner admit live steam again before the machine can be started, supposing that the expansive force of the steam in the chambers 13 is not sufficient to cause the resumption of rotation. Many forms of valve-throwing devices or other mechanisms could be employed to produce this action; but I have illustrated and described herein my preferred construction, which is as follows:

50^e is a lever pivoted at 50^d and engaging at 50^b with a grooved collar 50, adapted to slide longitudinally on one of the hubs of the casing-plate 7, and 50^a represents rod extending from this collar to and connected with the adjacent ring 7^b, so as to rotate therewith.

represents other rods, preferably having pulleys 51^a at their ends, traveling in grooves 52 in both rings 7^b, which grooves may be closed by plates 52^a, if desired. These latter rods 5 extend completely through the core and its flanges from one ring to the other, and said rings are of a thickness less than that of the disks 7^a, whereby they are permitted to have a slight movement longitudinally of the casting between the plates of the latter and the flanges of the core. With this construction, if the engine above described should be stopped after the cut off of live steam or other agent, to start it again it will be only necessary to operate the lever 50^c to move both rings simultaneously, so that the walls of their cam-grooves will throw the cut-off plate 20 in proper direction and to proper extent to bring the proper hole 20^a over the inlet-duct 6^b, leading to that side of the cylinder-head on which it is desired to admit steam, according as it is desired to start the engine in one direction or the other. The active agent in its full initial force is then and thereby admitted, the 25 engine resumes motion in a direction controlled by the way the spindle is set, and the lever 50^c is then immediately returned to its former position. Such valve-throwing device will not be necessary when a plurality of my 30 improved engines are connected with one driving-shaft in a manner similar to the arrangement of the cranks on a locomotive which are set quartering to each other. Neither will this device be necessary in connection with one of my improved engines 35 when a multiplicity of cylinder-heads are used in such manner as to prevent a dead-center.

At the bottom of Fig. 1 I have shown an auxiliary cylinder-head 10^m, which may be employed to shorten the length of stroke, here to make it one-third of a revolution. In Fig. 17 the dotted lines show where similar auxiliary heads 10^m might be located for substantially the same purpose. The inlet-ducts 6^b on opposite sides of this auxiliary head need not be provided with cut-offs, although the head is controlled in its movements by pins or pulleys 10^b, traveling in the cam-grooves 12, like the other heads. In this case the spindle 15 would have an auxiliary inlet-port 6^c, which would communicate with the inlet-duct 6^b and admit the full force of the live steam to the proper and desired side of the head 10^m. If the inlet-ducts 6^b for this head have no cut-offs, the second object of my invention is thereby accomplished, as it will be obvious that the continued full force of the live steam (without any expansion thereof) is employed against the auxiliary head and causes it to assist the other heads in driving the engine. Hence this form of engine would combine the expansive force of steam with its initial full direct force.

65 Referring now again to Fig. 7 and the holes 20^a in the cut-off plate 20, it will be obvious

that the lever 50^c may readily be given a longer stroke than that above described and possibly provided with a thumb-lever or other device for the purpose of holding it set at various points in its throw. The rings 7^b could also be made relatively thinner, so as to permit them to have a wider range of movement to and fro under the action of this lever. If now it should be desired to have the engine 75 run in either direction under the full force of the steam on all its heads 10 and 10^m, (and without any expansion at all,) the lever 50^c is so moved and set as to cause the valve-throw mechanism to move the rings to such 80 an extent that the hole 20^a will be squarely over the inlet-duct 6^b, and thereafter the lateral movements of the valve-plate 20 under the influence of the cam-grooves in the rings will only cause this hole to move to and fro 85 over, yet always in communication with, the inlet-duct. The result is that the cut-off no longer takes place at all, and hence more power is given the engine, although, of course, more steam is consumed; yet this feature of 90 my invention I consider extremely valuable, as it is thereby adapted to suddenly do very heavy work that may be thrown upon it, as in a locomotive-engine's ascending a heavy grade.

95 Thus it will be seen that this improved rotary engine can utilize both the direct force and the expansion of the steam on each of its heads, the same on certain heads combined with the direct force on others, or the direct 100 force on all of its heads, and that it can be stopped and started at any point and under any of the above conditions. I would further call attention to the fact that each cylinder-head is projected before the initial pressure 105 of the steam is received in the chamber 13 and recedes at a time when expansion has ceased in the form of engine shown in Fig. 1. Hence there is the least possible strain on the heads lateral to their chambers and approximately no binding action therein. In all cases and with all modifications the cam-grooves 12 follow accurately the configuration 110 of the active face of the rim, and hence while the packing at the outer edges of the cylinder-heads stands close enough to said active 115 face to prevent escape of steam or other agent between them still there is no appreciable friction and wear between the two at any point. Hence there can be no "pounding," as 120 is usual in engines of this type.

125 Fig. 9 shows my improved engine applied to a propeller-shaft which is journaled in bearings 27. The exhaust is at 30^a and the propeller at 28.

Fig. 10 shows two of my rotary engines mounted on the axle between the driving-wheels 26 26 of a locomotive.

Figs. 13 and 17 illustrate modified forms of the active face, &c., as above referred to.

130 It will be understood that such changes in, elaboration of, or additions to the details here-

inbefore set forth can be made as properly come within the spirit of my invention and that the precise shape, form, proportion, and arrangements of parts are immaterial save as 5 they serve to accomplish the desired ends.

What is claimed as new is—

1. In a rotary engine, the combination with a rim having cylindrical grooves at the interior of its ends and an interior active face between them, plates closing the ends of the rim, and disks carried by the inner faces of the plates and themselves provided with cam-grooves absolutely parallel with said active face; of a core concentric with the rim and provided with inlets and outlets for the active agent, cylinder-heads carried by the core and having pins engaging said cam-grooves for the purpose set forth, and flanges secured to the ends of the core, their outer edges traveling in the groove in the rim and their bodies standing between the core and the disks and having slots for the passage of said pins, substantially as set forth.

2. In a rotary engine, the combination with a shaft, a core thereon having radial chambers as well as outlets and inlets for the fluid agent, cylindrical flanges of greater diameter than the core and secured to its ends, packing in their outer edges, cylinder-heads reciprocating within said chambers, and packing along their outer edges between said flanges; of a rim surrounding the core and having concentric grooves at its ends within which the flange-packing works and an interior active face between the grooves and with which the cylinder-packing coacts, piston-heads in said active face consisting of packing set in the rim and screws for adjusting it, and means substantially as described for causing the cylinder-heads to advance and recede in conformity with the shape of the active face as the rim and core rotate the one with respect to the other, as set forth.

3. In a rotary engine, the combination with a hollow shaft mounted in supports, a rim loose on the shaft and having an interior active face with a plurality of piston-heads, a core fast on the shaft and having a plurality of cylinder-heads, and means for causing them to coact with said active face; of outlets leading from the steam-spaces between the active face and the periphery of the core, two sets of inlet-ducts leading from said spaces on respectively opposite sides of the cylinder-heads to individual openings arranged in one plane through said shaft, a rotatable hollow spindle within the shaft having ports adapted to register with either set, and a source of fluid-supply to the core of the spindle, as and for the purpose set forth.

4. In a rotary engine, the combination with a rim having an active face, piston-heads therein, a core within the rim, and cylinder-heads in the core coacting with said face; of inlet and outlet ducts through the core, cut-off plates for the former sliding in the core, rings carried by the rim and having cam-

grooves engaging the extremities of said cut-off plates, and a source of fluid-supply through the shaft, as and for the purpose set forth. 70

5. In a rotary engine, the combination with a rim having an active face, piston-heads therein, a core within the rim, and cylinder-heads coacting with said face; of inlet and outlet ducts, cut-off plates for the former sliding in the core, rings carried by the rim and having cam-grooves engaging said plates, these plates being also provided with concentric slots, set-screws taking through such slots and engaging the end plates of the rim, and a source of fluid-supply to the inner ends of the inlet-ducts, as and for the purpose set forth.

6. In a rotary engine, the combination with a rim having piston-heads in its active face, a core having a plurality of cylinder-heads coacting with said face and located out of diametrically opposite position, and outlets for the steam-spaces; of rings adjustably attached to the end plates of the rim and having cam-grooves, inlet-ducts for the steam-spaces, and independent cut-off plates across these ducts and within the core, the extremities of each plate traveling in its own cam-groove, as and for the purpose set forth.

7. In a rotary engine, the combination with a rim and a core member, one having an active face with piston-heads therein, and the other having cylinder-heads coacting with said face and inlets and outlets; of cut-off plates moving across the inlets, rings having cams for causing the movements of said plates, rods connecting the latter so as to cause their simultaneous movement, a collar to which one plate is connected, and a lever for moving the collar, as and for the purpose set forth.

8. In a rotary engine, the combination with rim and core members, one having an active face with piston-heads therein, and the other having cylinder-heads coacting therewith, and also having inlets and outlets; of cut-off plates moving across certain of said inlets while the others are permanently open, cams connected so as to move in unison and engaging the ends of said plates to cause cut-off at proper times, and a lever connected with the cams for permitting temporary inlet of the fluid agent, as and when desired.

9. In a rotary engine, the combination with a rim having an interior active face with piston-heads therein, end plates secured to the rim, a core within the rim having cylinder-heads coacting with said face and provided with inlet and outlet ducts, cut-off plates across the inlet-ducts, and flanges at the ends of the core; of rings standing between the end plates and flanges and provided with cam-grooves engaging the ends of said cut-off plates, and means for attaching the rings to the end plates, as and for the purpose set forth.

10. In a rotary engine, the combination with a rim having an interior active face with piston-heads therein, end plates secured to the

rim, a core within the rim having cylinder-heads coacting with said face and also provided with inlet and outlet ducts, and cut-off plates across the inlet-ducts; of disks secured 5 to the end plates and having cam-grooves, connections between such grooves and the cylinder-heads, rings surrounding the disks and also having cam-grooves engaging the cut-off plates, and means for adjustably securing the 10 rings to the end plates, as and for the purpose set forth.

11. In a rotary engine, the combination with a hollow shaft, a core fast thereon and having cylinder-heads, outlets leading from both 15 sides of the heads, inlets leading also from both sides thereof to two sets of individual openings into said shaft, and cut-off plates sliding in the core across the inlets; of a rim mounted on the shaft and having an active 20 face carrying piston-heads and with which said cylinder-heads coact, rings having cams engaging the ends of said plates, the rings moving relatively to the core, a spindle within the shaft leading the active agent from a 25 suitable source to its inlet-ports, and means for turning the spindle to throw its ports out of communication with one or both sets of ducts, as and for the purpose set forth.

12. In a rotary engine, the combination with 30 the rim and core members, one having an active face with piston-heads therein, and the other having cylinder-heads coacting therewith, and also having inlets and outlets; of cut-off plates moving across the inlets, means 35 for moving them at proper times, a collar connected with both such plates, and a lever for shifting the collar to temporarily interrupt the cut-off, as and for the purpose set forth.

13. In a rotary engine, the combination with the rim and core members, one having an active 40 face with piston-heads therein, and the other having cylinder-heads coacting therewith, inlets and outlets for each cylinder-head, and a cut-off plate across certain of the inlets and provided with holes twice the width 45 of the inlet-ducts; of means for reciprocating the plates at proper times to produce the cut-off of the fluid agent, and means for shifting the plates to bring their holes permanently across said ducts so that such cut-off may be 50 interrupted, as and for the purpose set forth.

14. In a rotary engine, the combination with the rim and core members, one having an active face with piston-heads therein, and the other having cylinder-heads coacting therewith, inlet and outlet ducts for each head and on each side thereof, a valve for admitting the fluid agent to whichever side of the heads is desired, and cut-off plates across certain of the inlets, each provided with a hole for each 60 inlet-duct which hole is twice the width of the duct and which two holes stand out of alignment; of means for reciprocating the plates at proper times to produce a cut-off in the inlet-duct in use, and means for shifting the 65 plates so as to bring one or the other hole permanently across its duct, whereby the reciprocation is not interrupted but the inlet is caused to remain open, as and for the purpose set forth.

In testimony whereof I affix my signature in presence of two witnesses.

DAVID M. DEARING.
